SHOWER HEAD

Emil Price and William A. Pfister,
Los Angeles, Calif.

Application November 5, 1934, Serial No. 751,625

6 Claims. (Cl. 299—130)

This invention relates to shower heads.

An object of the invention is to provide a shower head embodying means for enabling the shape of the spray or jet delivered therefrom to be controlled as desired and to meet varying requirements.

An important feature of the invention is directed to the novel construction and arrangements of parts employed by means of which either a flared spray of suitable size or a straight jet or column of substantially uniform diameter can be discharged from the head as may be desired and in some instances made necessary because of the particular environment in which the head is used. A shower head whose nozzle or discharge end is constructed for the exclusive discharge therefrom of a wide angle spray is ordinarily intended to be used in association with a shower stall of such dimensions as will enable the spray to be confined to a limited lateral area, to thus prevent the water from being deflected onto adjacent surfaces, such as the floor of a bath room in which the shower stall is a part. Because of the shape of the spray delivered from a head of this character, it has never been possible to use such heads in combination with ordinary bath tubs as the angle of the spray would project the water over the sides of the tub and onto the floor. The spray head forming the subject matter of this application is formed so that the size and shape of the spray can be readily controlled to enable same to be used in any one of the environments just above referred to.

It is a further object to provide a shower head which can be conveniently and quickly adjusted manually to suit any one of the conditions herein above mentioned.

To the end herein advanced and others that will manifest themselves as the description proceeds, the invention consists in certain improvements and combinations and arrangements of parts, as will be hereinafter fully set forth, with the features of novelty pointed out in the hereto appended claims.

In the drawing, wherein has been illustrated a preferred form of the invention,

Figure 1 is a vertical section taken through the complete head;

Figure 2 is a bottom plan view of the discharge end of the nozzle;

Figure 3 is a view in plan of one section of the head, with parts broken away and parts in section for the purpose of clearness;

Figure 4 is a schematic section through the

lower section of the head showing the parts in a position of relative adjustment to enable a wide angle spray to discharge from the head; and

Figure 5 is a section similar to Figure 4 showing the parts adjusted relatively to enable an attenuated stream to discharge from the head.

In carrying the invention into practice, use is made of a head consisting of co-operable sections A, B and C. The section A is formed at its upper end with an internal thread 10 to receive a water supply pipe P as is customary. The section A is formed with a water discharge bore 11 which opens into a hollow ball 12, threaded onto the reduced end 13 of said section. The ball is of a diameter to snugly fit in the cylindrical chamber 14 of section B and same is yieldingly pressed against a gasket 15 contained in the chamber, the same being supported by the annular flange 16. The upper portion of the section B is formed with an internally threaded enlargement 17 which adjustably accommodates a nut 18, the latter bearing against the marginal edge of a concavo-convex disk 19 of springy material. The central portion of the stock of the disk is formed with an opening 20 whose walls embrace the ball 12, as shown in Figure 1, whereby to force the ball into sealed engagement with the gasket 15, the parts co-acting as will be appreciated to prevent leakage of water around the ball. The section B is also formed with a reduced nipple 21 which opens to the ball 12 by way of a passage 22 formed therein. Said nipple 21 is provided with a base wall 23 having an annular series of outwardly flared openings 24 therein. At its center the wall 23 is provided with a stem 25 of a downwardly reduced diameter, the small end of which is provided with a conic frustum 26 whose large end is of a smaller diameter than the discharge orifice 27 in the head 28 of the section C.

The section C of the device has a skirt portion 29 of cylindrical form depending from the head 28 and fitting in said skirt is an annular member 30 formed with suitably spaced apart V-shaped flutes 31, against whose angular surfaces angularly delivered threads of water will be deflected as shown in Figure 1. It will be noted that the upper part of the frustum 26 is formed with an annular, downwardly and outwardly flared wall 32 which, when the frustum is in the position illustrated in Figure 1 functions to cause a downward angular deflection of the water against said flutes of the member 30, the deflection being wholly confined between the

upper and lower ends of said member. It will also be noted that the skirt 29 is of greater depth than the member 30, whereby to provide said skirt with a smooth annular surface 33 beneath the lower edge of said member whereby when the parts are adjusted relatively as shown in Figure 4 the angle of deflection of the threads of water will be such as to not cause material impingement of the water against said flutes 31.

10 From the head 28 of the skirt 29 rises an internally threaded sleeve 34 which co-acts with the nipple 21 to enable the sections B and C to be adjusted axially relatively to each other whereby to cause the position of the frustum 26

15 to shift relatively to the discharge orifice 27. The upper end of the section C is formed with an annular enlargement 35 which partly embraces the walls of the chamber 14. Said walls of the chamber are provided with an annular packing 36

20 which bears against the inner surface of the walls of the enlargement 35. The enlargement 35 has an internal resilient packing ring 36a which bears against the external surfaces of the enlargement 35, there being a nut 37 on the enlargement 35

25 which clamps the packing against the upper edge of said enlargement as shown in Figure 1.

When the sections B and C are adjusted relatively, as shown in Figure 1, the angle of deflection of the water pencils is such as to cause the water to impinge against the annular walls of the parallel flutes of the member 30, the member functioning to prevent spiral churning of the water in its movement through the skirt 29. In consequence thereof, a large diameter water column D will be formed. The diameter of this column will be the same as the internal diameter of the skirt 29.

When the sections B and C are adjusted relatively to slightly retract the frustum 26 into the orifice 27, the water as it leaves the orifice will be deflected at an angle that will prevent effective impingement of the water against the member 30. By making the member of a length that is less than the depth of the skirt 29, the water will be permitted to discharge at the angle shown in Figure 4, so that the device can be used in the manner of an ordinary spray head.

When the sections B and C are adjusted relatively as shown in Figure 5, the frustum 26 will be wholly retracted from the orifice 27 and the water will flow through the orifice and through the skirt 29 in the form of an attenuated stream E whose diameter is about the same as that of said orifice. In either of the first or last named positions of adjustment of the co-acting parts of the device, the transverse area of the stream of water will be confined within controlled lateral limits to enable the device to be placed above an ordinary bath tub so that use of the device will not result in projection of the stream laterally of the sides of the tub.

The ball connection 12 between the sections B and C provides a simple means for allowing the section C to be tilted off of the vertical center to enable the spray to be angularly projected as desired.

In a device as herein shown and described, we wish to particularly stress the use in combination of means such as the frustum 26, skirt 29, orifice 27 and member 30 for changing at will the angle of deflection of the water, to thus enable the shape of the delivered jet to be changed to meet the conditions herein set forth. To the best of our knowledge, we are the first in the art

to provide a spray head capable of functioning in this manner, and we shall expect to reserve to ourselves the right to make changes and alterations in the structure within the scope of the hereto appended claims without departing from the spirit of the invention. 5

What is claimed is:

1. A shower head comprising a hollow orificed ball; a section having a chamber in which the ball is contained; a gasket in the chamber; means for 10 yieldingly advancing the ball against the gasket to maintain a position thereof so that water entering the ball can leave same through the gasket by way of the orifice of the ball; means for connecting the ball with a water supply pipe; 15 a reduced portion on said section, the same having a depending stem formed with a conical portion; and a downwardly opening annular skirt connected with said section for movement axially relatively thereto and provided with an orifice 20 correlated to said conical portion to enable the latter to pass therethrough and project at respectively different distances into the chamber, said section having an annular series of openings 25 for discharging water into the chamber around said conical portion.

2. A shower head comprising an annular, downwardly opening skirt having a top wall formed with a central orifice and provided with an annular series of V-shaped flutes extending longitudinally of the inner walls thereof; and means for delivering water to the orifice from a supply line and including a conical element mounted relatively to the skirt for movement through the orifice and for projecting at respectively different distances into said skirt. 30

3. A shower head comprising an annular, downwardly opening skirt having a top wall formed with a central orifice and provided with an annular series of V-shaped flutes extending longitudinally of the inner walls thereof; and means for delivering water to the orifice from a supply line and including a conical element mounted relatively to the skirt for movement through the orifice and for projection at respectively different distances into said skirt, the flutes being of less length than the depth of the skirt. 35

4. A spray head for shower baths including a downwardly opening jet-discharge skirt having a member therein formed with an annular series of longitudinal V-shaped flutes, the length of which member is less than the depth of the skirt, the upper end of the skirt having a wall formed with an orifice opening downwardly into 50 the skirt; and means cooperable with the orifice and adjustable axially relatively thereto for changing the shape of the jet discharging from said skirt.

5. In a shower head, a large internal diameter skirt having a top wall provided with a small diameter axial opening through which water can pass into the skirt from a supply source; means including a water spreader adjustable from a position within the skirt and through the opening to a retracted position from the skirt and relative to the opening to enable a cylindrical stream of water of lesser diameter than the internal diameter of the skirt to be discharged from the 70 bottom of the latter; and means in the skirt cooperable with the spreader when the latter is in a position of predetermined adjustment in the skirt to cause a substantially cylindrical solid stream of water to discharge from the bottom of the 75

skirt, the diameter of which is substantially the same as the internal diameter of said skirt.

6. In a shower head, a large internal diameter skirt having a top wall provided with a small 5 diameter axial opening through which water can pass into the skirt from a supply source; means including a water spreader adjustable from a position within the skirt and through the opening to a retracted position from the skirt and relative to the opening to enable a cylindrical stream of water of lesser diameter than the internal diameter of the skirt to be discharged from the bottom of the latter; and means in the skirt co-operable with the spreader when the latter is in

a position of predetermined adjustment in the skirt to cause a substantially cylindrical solid stream of water to discharge from the bottom of the skirt, the diameter of which is substantially the same as the internal diameter of said skirt, 5 said skirt having an internal portion disposed with respect to said last named means so that when the spreader is in another position of predetermined adjustment water passing into the skirt and discharging therefrom will be converted into 10 a substantially conical spray.
